United States Patent Office.

PATRICK REILLY, OF READING, PENNSYLVANIA, ASSIGNOR TO SEYFERT,
McMANUS & CO, OF SAME PLACE.

Letters Patent No. 96,267, dated October 26, 1869.

IMPROVED FURNACE FOR HEATING TUBES.

The Schedule referred to in these Letters Patent and making part of the same.

I, PATRICK REILLY, of Reading, Berks county, Pennsylvania, have invented an Improvement in Furnaces for Heating Tubes, of which the following is a specification.

Nature and Object of the Invention.

My invention relates to an improvement in the furnaces used in the manufacture of lap-welded tubes; and consists of a peculiar arrangement, described hereafter, of furnace, fire-places, and outlet to the chimney, whereby a saving is effected, not only in the structure itself, both as regards material used and space occupied, but also in the consumption of fuel, while the tubes are more thoroughly heated throughout in my improved furnace than in those commonly used.

Description of the Accompanying Drawing.

Figure 1 is a side view of my improved furnace for heating tubes;

Figure 2, a vertical section on the line 1-2, fig. 1;

Figure 3, a sectional plan; and

Figure 4, a sectional plan of an ordinary tube-furnace.

General Description.

In figs. 1, 2, and 3, A represents the interior of the furnace, which is of length sufficient to admit the tubes, and of no greater breadth or height than is necessary to permit the free circulation of the ignited products of combustion round the tubes, each end of the furnace being provided, as usual, with a door, y.

Midway or thereabouts, between the opposite ends of the furnace, the latter communicates through an outlet-flue, a, with a chimney, B.

At each end of the furnace, and at right angles or thereabouts to the same, is arranged a fire-place, D, furnished with ordinary doors d and grate-bars e, and having a bridge, f, over which the ignited products of combustion pass into the interior of the furnace, in the direction pointed out by the arrows, to the chimney B.

The advantages of my improved tube-furnace will be best explained by comparing it with ordinary furnaces heretofore used in tube-works, a sectional plan of such a furnace being illustrated in fig. 4.

In this case one side of the furnace is entirely occupied by a series of fire-places, D, and on the opposite side is a massive and costly structure, containing

a series of flues, all of which communicate with a chimney, B.

Independently of the costly character of furnaces of this class, both as regards their construction, the enormous amount of fuel which they require, and the space occupied, there is a serious objection to them as regards the action of the flame on the tube placed on the bed of the furnace, for, as the flames from the fire-places take a nearly direct course across the furnace, from the different fire-places to the outlet-flues communicating with the chimney, as shown by the arrows, the tube (illustrated by dotted lines) must of necessity be subjected to a greater heat at some points than at others.

This want of uniformity in the heating of the tube is obviated in my improved furnace, for the ignited products of combustion, after passing over the bridges of the two fire-places and impinging against the ends of the tube, turn abruptly, and pass longitudinally through the furnace, along and in contact with the tube, meet at the flue a, and pass through the same to the chimney; the tube has thus the benefit of the flames throughout its entire length, and a uniform heat is imparted to it throughout.

It will be evident that by the arrangement of two fire-places, one at each end of the furnace, and a central flue communicating with the chimney, not only is the consumption of the fuel economized, but a more regular heat is maintained, and the tubes uniformly heated throughout, while the entire structure of the improved furnace is cheap and simple when viewed in comparison with the ordinary furnace, shown by fig. 4.

If desired, the fire-places may be situated at x x on one side of the furnace, and the outlet-flue on the opposite side; but I prefer the arrangement illustrated in fig. 3, as it tends to the economizing of space.

Claim.

The arrangement, substantially as described, of the furnace A, fire-places D D, and outlet-flue a to the chimney.

In testimony whereof, I have signed my name to this specification, in the presence of two subscribing witnesses.

PATRICK REILLY.
